FREDERIC C. SHUMAKER, OF SANGER, CALIFORNIA

TRAIN-ORDER-DELIVERY LIGHT

Application filed May 2, 1929. Serial No. 359,966.

This invention relates to a train order delivery light and it is an object of the invention to provide a structure of this kind to facilitate the delivery of a train order to a passing train and to permit such delivery to be effected with a minimum of danger to the person delivering the order.

It is also an object of the invention to provide means for positioning of the location from which delivery is to be made together with means for directing a beam of light in a manner to facilitate the collection of the train order by a fireman or other member of a train crew while the train is in transit.

An additional object of the invention is to provide a light of this kind supported in a manner whereby the same may be concealed out of the way when not in use and wherein the illuminating unit may be adjusted in a manner to direct a beam of light in opposite directions with respect to a trackway as may be occasioned by the direction in which the train is traveling.

A further object of the invention is to provide a device of this kind comprising a staff carrying a lamp or illuminating unit adapted to be adjusted into either of two fixed positions, said staff being mounted in a manner to permit the same to be positioned in substantially a vertical position and maintained in such position until released.

The invention consists in the details of construction and in the combination and arrangement of the several parts of my improved train order delivery light whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in perspective of a delivery light constructed in accordance with an embodiment of my invention, an asso-

ciated station platform and trackway being shown in fragment;

Figure 2 is a view partly in vertical section and partly in elevation of the structure directly associated with a lighting or illuminating unit, a second or inoperative position of said illuminating unit being indicated by broken lines;

Figure 3 is a view partly in section and partly in top plan of the structure as illustrated in Figure 2;

Figure 4 is a sectional view taken substantially on the line 4—4 of Figure 2;

Figure 5 is an enlarged fragmentary side elevational view of the upper portion of the staff and the illuminating member or unit mounted thereon;

Figure 6 is an elevational view of the structure as illustrated in Figure 5 directly to the rear of the illuminating member or lamp;

Figure 7 is a view partly in section and partly in top plan and also of a diagrammatic character indicating the two fixed positions adapted to be assumed by the illuminating member or lamp;

Figure 8 is a sectional view of the lower portion of the staff.

As disclosed in the accompanying drawings, P denotes a platform of any conventional or preferred construction which has its curve 1, as is customary, disposed in relatively close proximity to the outer rail 2 of an adjacent trackway.

Placed within the structure of the platform P is a casing C of desired dimensions and configuration, the upper face of which being open and adapted to be closed by a door or lid D of any desired type. The casing C, as herein disclosed, is oblong in form and in practice the casing C is placed within the platform P with the outer longitudinal wall of the casing spaced approximately seventy-two inches from the center of the adjacent rail 2. Mounted upon the bottom wall 3 of the casing C immediately adjacent to an end wall 4 thereof are the transversely spaced bearing blocks 5 which provide a mounting for an end portion of an elongated staff S. This staff S comprises an elongated tubular member 6 of desired length having one end

portion in threaded engagement with a leg 7 of a four-way coupling A.

The opposed leg 8 provides an entrance for a conductor 9 leading from a suitable source of electrical energy and extending through the member 6 for proper connection with the conventional bulb positioned within the illuminating unit or lamp L carried by the upper or outer end portion of the staff S. The side or lateral legs 10 of the coupling A have threaded therewith the oppositely disposed tubular trunnions 12, one of which being herein disclosed of greater length than the other and both of which having their outer ends closed by the caps 14. These trunnions 12 have direct engagement with the bearing blocks 5 whereby the staff S is mounted for swiveling movement in a vertical direction. The interior dimensions of the casing C are such that when the staff S is swung downwardly said staff together with the unit or lamp L will be completely housed within said casing C, as indicated by broken lines in Figure 2 of the accompanying drawings.

When the staff S is lowered within the casing C the outer portion thereof rests upon and is supported by a suitably positioned block or bolster 15 mounted upon the bottom wall 3 of the casing C.

The conductor 9 within the member 6 and closely adjacent to the coupling A has interposed therein a conventional switch which is adapted to be opened and closed in a well known manner by a sliding operator 16. This operator 16 is slidably directed through the member 6 and when moved in one direction results in the closing of the switch and upon movement in the opposite direction to open the switch. When the staff S is swung upwardly to its vertical position, the operator 16 in the present embodiment of my invention has contact with an inwardly disposed lug 17 carried by the adjacent end wall 4 resulting in the operating circuit for the lamp or lighting unit to be closed, and when the staff S is swung down within the casing C this operator 16 has contact with an upstanding lug 18 suitably positioned upon the bottom wall 3 of the casing C resulting in the switch being opened.

The end wall 4 adjacent to the staff S is provided with the inwardly directed spring jaws 19 which receive therebetween and frictionally engage the staff S when raised and serve to maintain the staff in its desired elevated position until released by an employee.

The lamp or lighting unit L, as herein disclosed is constructed in accordance with a conventional and well known type of spot light and said lamp or member proper is disposed laterally from the upper end portion of a barrel or sleeve 20 snugly engaged with the upper portion of the member 6 of the staff S. This lamp or unit L is also disposed upwardly on an angle of about forty degrees

with respect to the longitudinal axis of the barrel 20. The lower end portion of the barrel 20, or that end portion disposed inwardly of the member 6, is defined by an outstanding flange 21 with which coacts from above an inwardly disposed flange 22 carried by a nut 23. This nut 23 threads upon a sleeve 24 surrounding the member 6 and fixed thereto in any desired manner.

The mounting of the barrel 20, as herein disclosed, permits the same to readily rotate around the member 6 of the staff S but is effectively held against endwise movement thereby eliminating displacement. The wall of the member 6 within the barrel 20 is provided with a pair of circumferentially spaced openings 25 with which is adapted to selectively register an opening 26 in the wall of the barrel 20. The barrel 20 exteriorly thereof carries a lever 27 pivotally supported, as at 28, at a desired point, one end of which having an inwardly disposed nose 29 for passage through the opening 26 and an aligning opening 25 whereby the member or unit L will be fixedly held in either of its two positions. The opposite end portion of the lever 27 has coacting therewith a leaf spring 30 carried by the adjacent end portion of the barrel 20, said spring 30 operating to constantly urge the nose 29 inwardly.

When the lamp or unit L is in either of its two fixed positions the beam of light emitted therefrom is on an upwardly disposed angle and also on an angle toward the track so that when a person takes a proper position at a desired side of the lamp or unit L and extends his arm outwardly the conventional message hoop carried by the hand of such extended arm will be directly within said beam of light. This will result in effective illumination of the hoop with no light rays in the eyes of said person or of the firemen or other member of the crew on the approaching train who is to catch the hoop.

At a desired distance beyond either end of the casing C the platform P is provided with a suitable indication 31 to denote the position to be taken by the person to deliver the message and it is to be noted that the staff S when raised into working position is substantially midway the indications 31 so that the beam of light will be effective when disposed in either of its two positions. In practice, I find it of advantage to have the indications 31 spaced apart ten feet and also to have said indications 31 positioned inwardly from the curve 1 of the platform to assure approximately six feet from the adjacent rail 2. It is preferred that the beam of light be disposed toward the trackway on an angle of approximately thirty degrees.

From the foregoing description it is thought to be obvious that a train order delivery light constructed in accordance with my invention is particularly well adapted for

use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. In combination with a station platform and a trackway adjacent thereto, an illuminating member, and means for supporting said member on the platform to throw a beam of light on an upward incline and in a direction lengthwise of the trackway and also in a direction toward said trackway.
2. In combination with a station platform and a trackway adjacent thereto, an illuminating member, and means for supporting said member on the platform to throw a beam of light on an upward incline and in a direction lengthwise of the trackway and also in a direction toward said trackway, said illuminating member being rotatably engaged with its supporting means to permit the member to throw its beam selectively in either direction lengthwise of the trackway.
3. A device of the class described comprising a casing, an elongated staff, means for swingly mounting one end portion of the staff within the casing to permit the staff to be raised from the casing or lowered therein, resilient clamping means carried by a wall of the casing and coacting with the staff to hold the staff elevated, and an illuminating member carried by the opposite end portion of the staff.
4. A device of the class described comprising a casing, an elongated tubular staff, oppositely disposed and laterally directed trunnions carried by one end portion of the staff, bearings mounted in the casing with which the trunnions engage to permit the staff to raise or lower, an illuminating member of an electrical type carried by the opposite end portion of the staff, and conductors for the illuminating member extending through the tubular staff.
5. A device of the class described comprising a casing, an elongated tubular staff, means for swingingly mounting one end portion of the staff within the casing to permit the staff to be raised from the casing or lowered therein, clamping means carried by a wall of the casing and coacting with the staff to hold the staff elevated, and an illuminating member carried by the opposite end portion of the staff, the top of the casing being open, and a lid for closing said opening.
6. A device of the class described comprising an elongated staff, means coacting with an end portion of the staff to permit the staff

to be raised or lowered, means for holding the staff raised, a barrel rotatably engaged with the opposite end portion of the staff, said staff being provided with a pair of circumferentially spaced recesses, the wall of the barrel having an opening for selective register with said recesses, and a latch carried by the barrel extending through the opening thereof and within a registering recess to hold the barrel against rotation, and an illuminating member carried by the barrel.

In testimony whereof I hereunto affix my signature.

FREDERIC C. SHUMAKER.
